CLAIM

The ornamental design for a folding cabinet step, as shown and described.

DESCRIPTION

FIG. 1 is a perspective view of a folding cabinet step showing my new design, it being understood that the broken lines are for illustrative purposes only; FIG. 2 is an enlarged side elevational view thereof, the opposite side being a mirror image of that shown; FIG. 3 is a front elevational view of FIG. 2; FIG. 4 is a top plan view of FIG. 2; and FIG. 5 is a rear elevational view of FIG. 2.
